UNITED STATES PATENT OFFICE

PETER C. PETERSEN, OF CEDAR FALLS, IOWA, ASSIGNOR TO VIKING PUMP COMPANY,
OF CEDAR FALLS, IOWA

ROTARY ENGINE

Application filed November 28, 1927. Serial No. 236,166.

My invention relates to a rotary engine which may also be employed as a rotary pump.

One object of the invention is to provide an engine of this character which will be simple in construction and comparatively inexpensive, but which at the same time will be efficient in operation and capable of producing an exceptional amount of power when used as an engine, and a strong, steady flow of fluid when used as a pump.

10 Another object is to provide a rotary engine having an improved construction of rotor and means whereby the rotor will be firmly held in operative position in the casing.

15 With the foregoing and other objects in view, the invention consists in the novel features of construction hereinafter pointed out and claimed, reference being had to the accompanying drawings, in which:

20 Figure 1 is a longitudinal, horizontal section taken through the center of the casing and showing the rotor in full lines.

Figure 2 is a vertical cross section taken on the line 2—2 of Figure 1.

25 Figure 3 is a similar view taken on the line 3—3 of Figure 1.

Figure 4 is a perspective view of the rotor and one of the end cover plates of the casing showing the manner in which the cams on the 30 cover plate act on the blades or vanes of the rotor.

Figures 5 and 6 are diagrammatic end elevations of the casing showing more clearly the arrangement of the inlet and outlet ports and channels connecting the same.

In the drawings, 1 denotes the cylinder or cylindrical casing which is preferably cast integral with a suitable supporting base 2. The cylinder or casing is open at both ends

40 and has formed in one side an external intake port 4 and in its opposite side an external discharge port 5. These ports are disposed directly opposite to each other, and projecting from the sides of the casing around these 45 ports are oppositely-disposed, internally threaded bosses or sockets 6 for the reception of piping through which fluid enters and is discharged from the casing.

The intake port 4 communicates at its inner 50 end with two inlet channels 7 and 8 which

are formed in the adjacent side of the casing and which communicate at their inner ends with internal inlet ports 9 and 10.

The discharge port 5 communicates at its inner end with two outlet channels 11 and 12 formed in the adjacent side of the casing and which in turn communicate at their inner ends with two outlet ports 13 and 14.

These internal inlet and outlet ports are located near the opposite ends of the casing and are so arranged that there will be one inlet and one outlet port disposed directly opposite to each other in each end of the casing.

The cylinder or casing is preferably provided with a bushing 15 which extends through and is preferably sweated into the casing, but which may be secured therein in any suitable manner. The bushing is provided with openings which align with the 60 internal inlet and discharge ports.

The open ends of the cylinder or casing are closed by removable cover plates or heads 16 which are preferably secured to the ends of the casing by screws 17 which engage threaded openings in said ends of the casing. Suitable gaskets are disposed between the cover plates and ends of the casing to form fluid tight joints between these parts.

On the outer sides of the cover plates are 65 tubular extensions 19, which form bearings for the ends of the rotor shaft, and which are provided with suitable bushings and stuffing boxes to form a fluid tight bearing. In the inner sides of the cover plates or cylinder 70 heads 16, and concentric with the bearing openings therein, are annular recesses 20, the purpose of which will be hereinafter described.

On the inner sides of the cylinder heads or 75 cover plates are arranged cam-shaped abutments 21 which are preferably formed integral with the heads, and project into the ends of the casing. Each abutment is formed with two segmental-shaped cam surfaces 22 which 80 extend in opposite directions from the central high part or block of the abutment and incline to the inner surface of the plates or heads. The abutment cams are so arranged on the 85 heads that, when the engine is assembled, the 90

95

100

highest part of the abutment on one cylinder head will be directly opposite the lowest part of the abutment on the other cylinder head.

Rotatably mounted in the cylinder or casing is a cylindrical rotor or piston 23 which is keyed or otherwise securely fastened to a shaft 24 mounted in the bearings in the cylinder heads. On the opposite ends of the rotor are formed cylindrical projections 25 which extend into the annular recesses 20 in the cylinder heads and hold the rotor against endwise movement or thrust and also steady the rotor in its rotation. The rotor or piston is provided with a plurality of longitudinally disposed, radially extending slots or passages 26, the lower portions of which extend entirely through or across the cylindrical projections 25 on the ends of the rotor as clearly shown in Figure 4 of the drawings.

In the slots or passages 26 are mounted the blades or vanes 27 of the piston, said blades being adapted to slide back and forth in the slots 26 under the action of the abutment cams which engage the ends of the plates at their outer edges. The cam engaged portions of the ends of the blades are beveled to form V-shaped cam-engaging surfaces, as shown at 28 in Figure 4. By thus forming the cam engaging portions of the ends of the blades friction between the same and the surfaces of the cams is reduced. The inner edges of the blades which engage and slide on the bottoms of the notches are flat, while the outer edges of the blades are slightly rounded to conform to the annular surface of the casing or the bushing therein.

In the annular recesses 20 of the cylinder heads are preferably, but not necessarily, seated flat collars or wear plates 29 against which the ends of the projections 25 on the ends of the piston or rotor bear.

In the operation of the device, the cam surfaces of the abutments alternately shift the blades back and forth through the slots in the piston, and, when used as an engine, steam or other fluid under pressure enters the intake port on one side of the cylinder or casing and passes through the inlet channels and into the cylinder and forcibly engages the blades as they are alternatively projected into the opposite ends of the cylinder by the cam abutments. As the blades are alternatively retracted from the opposite ends of the cylinder, the exhausted steam will be discharged through the outlet channels and ports in the opposite side of the cylinder as will be readily understood.

When the device is used as a pump, the piston is rotated by power applied to the shaft, and the blades are reciprocated in the piston as previously described. As the blades are thus alternatively projected into and retracted from the opposite ends of the cylinder, the water or other fluid will be drawn into the cylinder through the intake ports

and channels in one side of the cylinder or casing and expelled through the outlet channels and ports in the opposite side of the cylinder. This intake and expulsion takes place alternatively and simultaneously at both ends of the cylinder, causing a constant stream to flow from the outlet port.

While I have shown and described the preferred construction, variations may be made within the scope of the invention as claimed.

I claim:—

In a rotary engine, a cylinder casing having open ends, opposed inlet and outlet ports and a plurality of sets of internal inlet and outlet channels, the inlet and outlet channels of each set communicating with the inlet and outlet ports respectively and being arranged in opposed relation within the casing, and the respective sets of channels being arranged side by side, cover plates secured to the open ends of the cylinder casing and having cam members fitted therein, lying outwardly of the plane of the opposed inlet and outlet ports, a shaft journalled in the cover plates, a rotor fixed on said shaft, and a one piece annular bushing interposed between the rotor and cylinder casing, said bushing being fitted between the cam members and the cylinder casing and clamped in position thereby, said bushing having sets of inlet and outlet ports therein communicating with the channels in the casing for the flow of fluid.

In testimony whereof I affix my signature.
PETER C. PETERSEN.
